UNITED STATES PATENT OFFICE.

LEONARD GODFREY PINNEY THRING, OF GUILDFORD, ENGLAND:

SIGHT FOR RIFLES AND OTHER SMALL-ARMS.

No. 799,206.

Specification of Letters Patent.

Patented Sept. 12, 1905.

Application filed April 18, 1905. Serial No. 255,398.

To all whom it may concern:

Be it known that I, LEONARD GODFREY PINNEY THRING, a subject of the King of Great Britain and Ireland, residing at Ploncks Hill, 5 Shamley Green, Guildford, in the county of Surrey, England, have invented new and useful Improvements in and Connected with Sights for Rifles and other Small-Arms or Artillery, of which the following is a specification.

My invention relates to sights for rifles and small-arms and is also applicable to artillery.

The object of the invention is to provide a form of sight which allows a much clearer 15 view of the object aimed at than is obtained with any non-telescopic sight at present in use.

In the method at present employed the back sight and fore sight are both sighted on the object aimed at—that is, the rifle is so held 20 that the object aimed at, the fore sight, and the back sight are in one straight line, which line of course also contains the eye of the person shooting. The result of the back sight having to be got on this line is that a portion 25 of the light coming from the object aimed at is intercepted by the back sight on its way to the eye, thus producing a certain haziness which becomes very marked in a weak light. To remedy this, the orthoptic sight has been 30 proposed, in which a small hole in a disk takes the place of the back sight. By my invention, however, this difficulty is overcome in a totally different manner.

I shall describe my invention with reference 35 to a simple form of sight, and in the description which follows I shall call the line containing the eye the "fore sight," and the object aimed at "the line of sight." In order that the bullet may strike the object aimed 40 at, the barrel of the gun must make a certain angle with the line of sight, depending on various considerations, such as range and wind. Now in the ordinary gun-sights as heretofore constructed this angle is determined by get- 45 ting a certain point on the back sight in the line of sight, thereby giving rise to the disadvantages mentioned above.

My invention consists in fixing the angle between the barrel of the gun and the line of 50 sight by means of a back sight which is outside the line of sight and a subsidiary sight attached near the fore sight.

The invention further consists in arranging the back sight and subsidiary sight in such a

manner that the shooter can select different 55 points on said sights for the purpose of making allowance for range.

The invention also consists in the forms of sight hereinafter described.

In aiming a gun according to my invention 60 I get the eye, the fore sight, and the object aimed at all in one line, and the eye, the back sight, and the subsidiary sight all in another line.

Referring to the accompanying drawings, 65 Figure 1 is a view of one form of my improved fore sight and subsidiary sight, while Fig. 2 is a view of a back sight suitable for use with the same, Fig. 3 being a view of another form of fore sight and subsidiary sight, and 70 Fig. 4 a back sight intended to be used with the sights shown in Fig. 3.

Now it is clear that the point selected on the back sight may be an aperture which is made to coincide with an opaque portion or an aperture in the subsidiary sight, or an opaque portion of the back sight may be made to cover an aperture or opaque portion in the subsidiary sight. Now according to this invention I take 75 several such apertures or opaque portions and arrange them vertically above one another to form the back sight, and in a similar way I take several such opaque portions or apertures 80 and arrange them above one another to form a subsidiary sight, taking care that the apertures and opaque portions forming the back sight are of such a size as optically to register with the opaque portions or apertures forming the subsidiary sight. Also I may 85 arrange the apertures or opaque portions of 90 the subsidiary sight horizontally or both vertically and horizontally. The result of having a series of such apertures or opaque portions in the sights is that the shooter can select a particular point on the back sight and 95 align it with a particular point on the subsidiary sight and can thus make allowance for range, windage, &c.

I prefer to so arrange my opaque portions or apertures on the back sight which have to 100 coincide with the apertures or opaque portions on the subsidiary sight as to obtain what I call a "balance." I will explain what I mean by this by reference to a concrete instance. Suppose that a particular point on the back 105 sight is formed by the intersection of two opaque lines and I form the aperture in the subsidiary sight as a square. Then I can accu-

rately estimate when the intersection of the lines lies over the center of the square aperture by the fact that when in this position the portions of the aperture showing on the two sides of the vertical line will be equal in size, and similarly for the horizontal line. It is clear that I might equally well obtain a balance with intersecting lines in the back sight if the point in the subsidiary sight consisted 10 of a square opaque disk, for then I should balance the horizontal line across the vertical edge of the disk for vertical position and the vertical line across the horizontal edges of the disk for horizontal position.

15 A similar effect to that produced by apertures can be obtained by a light-colored paint or its equivalent, and this method may be used where practicable.

In the arrangement I have illustrated in 20 Figs. 1 and 2 the subsidiary sight *a* is in one piece with the fore sight *b* and is formed in the shape of a vertical bar with horizontal teeth *c c d d d*, of which alternate teeth *c c* are longer than the others, as shown in Fig.

25 1, a vertical bar *e* extends upward to the same height as the subsidiary sight on the left-hand edge of the sight. A light-colored vertical band *u* may be painted or otherwise applied to the subsidiary sight to render the teeth on 30 the back sight more visible in a bad light.

The back sight *f* consists of a plate fixed to the barrel in any convenient manner, preferably on a hinge, so that it is capable of lying along the barrel. A long vertical rectangular slot is cut in the left-hand side of the plate, projecting teeth *g* being left on the right-hand edge of the slot and also one or more teeth *h k* on the left-hand edge. In this arrangement the person shooting places the fore sight 35 in the line between the object and the eye and alines the gun so that the whole of the fore sight and subsidiary sight can be seen centrally between the edges of the vertical slot in the back sight—that is to say, he turns the gun about a vertical axis until equal spaces 40 are seen between the outside edges of the subsidiary sight and the edges of the vertical slot in the back sight, and thus obtains a balance.

To obtain the correct elevation, the shooter, 45 keeping the fore sight on the object and preserving the balance already obtained, arranges one of the horizontal teeth *g* of the back sight so as to cover one of the horizontal teeth *c c d d d* on the subsidiary sight, as may be desired.

By arranging that two long teeth or two short teeth of the subsidiary sight are seen at equal distances on each side of a horizontal tooth on the back sight a balance is obtained 50 which determines the angle of elevation of the gun, or I may balance a horizontal tooth on the back sight between any two teeth of the subsidiary sight.

In order to sight the gun for the shortest

range, the person shooting balances the lowest of the bars *g* of the back sight on the central tooth *d* of the subsidiary sight. For a slightly longer range he would balance the same tooth of the back sight on the lower tooth *c* of the subsidiary sight. For a still longer range the same tooth of the back sight would be balanced on the lowest tooth *d* of the subsidiary sight, and the distances between the teeth of the sights are so arranged that when the lowest tooth of the back sight is balanced 75 on the lowest tooth of the subsidiary sight the second tooth on the back sight is balanced on the highest tooth *d* of the subsidiary sight. For longer ranges the person shooting would first use the second tooth of the back sight 80 and take the teeth of the fore sight in order downward and for increasing ranges the third tooth from the bottom of the back sight, and so on. The teeth *h k* are provided to assist the person shooting in the rapid selection of 85 the proper tooth of the back sight to be used for any particular range. I thus obtain a very large number of sighting-points and a convenient means of sighting for small differences of range.

The whole face of the fore sight and the left-hand side of the back sight are preferably of a dark color, and the back sight may conveniently be marked with the different ranges on its right-hand side.

95 The arrangement above described is the one which I have found to be the best and which I prefer to use; but I may vary the details of my sighting means and still obtain good results. One such variation I have shown in 100 Figs. 3 and 4. In this arrangement the subsidiary sight *l* is in one piece with the fore sight *m* and is formed as a vertical bar with horizontal teeth *n* of rectangular form with projections *1 1* at their angles. On the left-hand side the vertical bar *l* carries a horizontal projection having a rectangular plate *o* at its end, the plate *o* being notched, as shown at *p*. Light-colored disks *2* may be fixed to the plate *o* on the side nearest the eye. The back sight *q* 105 consists of a plate fixed to the barrel as in the previous modification. Vertical slots one above the other, with projections *r s t*, are cut in the plate, three projections being shown in each slot, the projections differing in shape, 110 as shown in Fig. 4, for convenience in selection by the person shooting. In this arrangement the person shooting places the fore sight in the line between the object and the eye and alines the part of the back sight which is between the slots and the left-hand edge centrally across the rectangular plate *o*, so as to obtain a balance.

115 For elevation the person shooting, as in the previous modification, arranges one of the projections *r s t* of the back sight so as to cover one of the teeth *n* or spaces between the teeth of the subsidiary sight, and thus

obtains a balance. It will be seen that in this modification, as in that first described, if the subsidiary sight is near the muzzle of the gun equal distances in a vertical line 5 on the subsidiary sight will correspond with very much smaller differences of range than the same distances on the back sight, and I prefer to make the two sights of such proportions and to so place them that the distance 10 between two consecutive apertures or opaque portions on the back sight corresponds with the distance between the extreme apertures or opaque portions of the subsidiary sight. For a short range the person shooting 15 would select the lowest aperture or opaque portion on the back sight and the central aperture or opaque portion on the subsidiary sight and for steadily increasing ranges would take the apertures or opaque portions 20 on the subsidiary sight in order downward to the bottom and would then proceed in the same way, using the next higher aperture or opaque portion on the back sight, but starting from the highest aperture or opaque portion 25 on the subsidiary sight. The central aperture or opaque portion on the subsidiary sight is used for the point-blank range as being the most readily selected for rapid aiming.

In the arrangement illustrated in Figs. 3 and 4 I have shown a number of small light-colored disks, one of which is fixed on each projection of the subsidiary sight. I have found that the light-colored disks on the projection γ assist greatly in obtaining the balance in a horizontal direction. It will be seen that by properly choosing the bar or projection on the back sight and the disk or tooth or space between teeth on the subsidiary sight I can obtain a very fine adjustment of sighting 35 and that the arrangement of the various points which may be used for sighting is such that confusion will not arise as to the points which the shooter has selected for a given range.

Having now described my invention, what

I claim as new, and desire to secure by Letters Patent, is—

1. A sighting device comprising in combination, a subsidiary sight outside the line of sight having a number of definite sighting-points, and a back sight outside the line of sight also having a number of definite sighting-points, as and for the purposes described. 50

2. A sighting device, comprising in combination, a fore sight, adapted to be brought into the line between the eye and the object aimed at, and a back sight and subsidiary sight outside of said line, substantially as described. 55

3. A sighting device, comprising in combination, a fore sight adapted to be brought into the line between the eye and the object aimed at, and a back sight and subsidiary sight outside of said line, said back sight and subsidiary sight being provided with a number of definite sighting-points, substantially as described. 60

4. A sighting device, comprising in combination, a fore sight adapted to be brought into the line between the eye and the object aimed at and a back sight and subsidiary sight outside of said line, and a number of teeth or projections on said subsidiary sight adapted to be alined with teeth or projections on the back sight, as and for the purposes described. 70 75

5. A sighting device comprising a fore sight adapted to be brought into the line between the eye and the object aimed at, a back sight and subsidiary sight outside of said straight line, and means for obtaining a number of sighting-points corresponding with small differences of range, substantially as described. 80

In testimony whereof I have signed my name to this specification in the presence of two subscribing witnesses.
